REMOVABLE ABSORBING AGENT UNIT FOR
GAS ANALYZERSCharles A. Sprague, Michigan City, Ind., assignor
to The Hays Corporation, Michigan City, Ind.,
a corporation of Indiana

Application August 30, 1939, Serial No. 292,573

9 Claims. (Cl. 23—254)

This invention relates to improvements in removable absorbing agent unit for gas analyzers, and more particularly to a unit containing phosphorus and adapted primarily for an oxygen analyzer.

The value of phosphorus as an absorbing agent for oxygen is well known. However, no practical manner for the use thereof in a gas analyzer of the Orsat type has ever been known heretofore. Consequently, it has generally been necessary in order to obtain a measure of oxygen content in a gas, to use a less dangerous absorbing agent such as pyrogallic acid, which will absorb oxygen and some other constituent of the gas, such as carbon dioxide. At the same time that one sample of the gas is being analyzed as the aforesaid, another sample of the same gas is analyzed by the use of an absorbing agent, for the carbon dioxide only, such as caustic soda. A comparison of the results obtained and a computation of the difference in the two readings gives the oxygen content. This method is naturally subject to the disadvantages of a double operation together with the necessity of mathematical computation.

The phosphorus is very dangerous to handle and this danger is one factor which has prevented its use in Orsat analyzers heretofore. Another factor which has made the use of phosphorus in gas analyzers difficult is the rapid formation of phosphorous pentoxide (P_2O_5) which coats the phosphorus and must be washed away in order to maintain full absorptive properties of the phosphorus.

Therefore it is the primary object of this invention to provide novel and simple means to facilitate the use of phosphorus as an absorbing agent in a gas analyzer.

A further object is to provide a gas analyzer utilizing phosphorus as an absorbing agent, wherein provision is made to avoid the absorption-retarding effect of corrosion of the phosphorus, and wherein a simple apparatus to facilitate recharging with the phosphorus is provided.

A further object is to provide a container for an absorbing agent such as phosphorus, which may readily be applied to and removed from a gas analyzer by an operator in substantially the same condition in which the container is received from the manufacturer, and without necessity of opening the container or handling the phosphorus.

A further object is to provide a container for a gas absorbing agent with attachment means associated therewith, which means is of a character adapted for attachment of the container to

either a gas analyzer or a shipping container without exposing said agent to manual contact.

A further object is to provide a novel container for phosphorus by means of which the same may be immersed in water while being shipped.

10 A further object is to provide a phosphorous container adapted to be inserted in a gas analyzer, and provided with means for feeding the phosphorus to a position of maximum efficiency for absorption as necessary in use thereof.

Other objects will be apparent from the description and appended claims.

In the drawings:

15 Fig. 1 is a side elevation of the upper portion of a gas analyzer having the casing portion thereof shown in section.

Fig. 2 is a side elevation of the lower portion of the gas analyzer, with parts shown in section.

20 Fig. 3 is a vertical sectional view of a shipping container for my improved absorbing agent unit and illustrating the latter in operative position in said casing.

Fig. 4 is a vertical sectional detail view of my absorbing agent unit illustrating the manner in which the same is mounted in the analyzer.

Fig. 5 is an enlarged top plan view of the plate of my unit which mounts the absorbing agent.

30 Fig. 6 is a vertical sectional view taken on line 6—6 of Fig. 5.

Fig. 7 is a fragmentary diagrammatic view of the analyzer illustrating the measuring chamber thereof, and associated parts.

35 Referring to the drawings, which illustrate the preferred embodiment of my invention, the numeral 10 indicates the casing of a gas analyzer from which depends a bracket 11 which in turn supports a casing 12 therebelow.

40 On top of the casing 10 is mounted an aspirator 13 having a suitable valved water intake 14, and a gas intake 15. Within casing 10 is mounted a standpipe 16 communicating with aspirator 13. Standpipe 16 includes a laterally projecting portion 17 at its lower end, and a laterally projecting portion 18 adjacent its upper end.

45 A water tank 19 is mounted within the casing 10 spaced above portion 17 of the standpipe. Within the tank 19 is fixedly mounted a burette 20. The burette is interposed in a gas passage system best illustrated in Fig. 7, wherein a conduit 21 projects downwardly from the lower end of the burette and into the standpipe portion 17. A conduit 22 extends vertically upwardly from the top of the burette. A conduit 23 branches from con-

duit 22 and extends downwardly to terminate within the standpipe portion 17. A gas supply conduit 24 extends from the aspirator 13 to the conduit 23 with which it communicates at a point below the level of the bottom of burette 20. A pair of conduits 25 and 26 branch from conduit 21 at different levels thereof, and extend vertically upwardly. Conduit 25 is open to atmosphere, and conduit 26 communicates with an atmospheric bag 27 preferably formed of rubber and hereinafter referred to as an atmospheric bag. Conduit 25 joins conduit 21 opposite the point of connection of conduits 23 and 24; and conduit 26 joins conduit 21 above the point of connection of said conduits 23 and 24. A syphon 28 has one leg thereof communicating with the standpipe 16, and the other leg 29 thereof passing through the bottom of casing 10 and into the top of lower casing 12. The bight or upper portion 30 of syphon 28 projects slightly above the level of the upper end of standpipe projection 18. A second syphon 31 is positioned within casing 12 with its upper portion 32 positioned adjacent to the level of the lower portion of syphon run 29, and has a discharge run 33 opening below the bottom of casing 12.

An absorption chamber 34, best illustrated in Fig. 4, is mounted within water chamber 19, said absorption chamber being open at its lower end. A compression chamber 35 is placed in communication with water chamber 19 and has an open ended calibrating tube 36 mounted vertically within its top and adjustably positioned therein. A syphon 37 has one leg thereof within chamber 35 adjacent to the bottom thereof, and passes outwardly of said chamber with its upper portion spaced below the top of calibrating tube 36. The external vertical run 38 of syphon 37 is connected with an extra supply tank 39 within the casing 10 and below the level of chamber 35. A conduit 40 communicates with the upper end of chamber 39, and projects downwardly to enter the casing 12. A bell 41 is positioned within casing 12 adjacent to the bottom thereof, with its bottom surface slightly above the level with the inner end of syphon 31. Conduit 40 communicates with bell 41. A bell 42 is mounted in the upper end of standpipe portion 18 and is connected with the conduit 43 by means of a fitting 44. Conduit 43 extends to a suitable bellows (not shown) of the recording or indicating mechanism of the analyzer. A conduit 45 is connected by a suitable fitting 46 with the upper end of compression chamber 35. Conduit 45 extends to and communicates with a second bellows (not shown) of the indicating or recording mechanism of the analyzer.

Referring now more specifically to the absorption chamber 34, best shown in Fig. 4, the same preferably comprises a cylindrical housing member open at both ends. At the upper end of the said housing member is mounted a head 46 including a reduced neck portion 47, and an enlarged flange 48 adapted to overlie the upper end of the cylindrical member of the housing and to project outwardly therefrom, and a portion 49 extending within the upper end of the cylindrical housing. Head 46 has a conical opening 50 formed centrally therein and tapering from the lower end thereof to a restricted diameter passage 51 extending centrally through neck 47. Head 46 is preferably welded to the cylindrical body 34. A gasket ring 52 fits around cylindrical body 34 and bears against the lower surface of flange 48. A plurality of pins or studs 53 are

carried by the lower end of cylindrical housing 34 to project inwardly thereof. On these pins is normally supported a block 54 adapted for vertical movement within the housing 34. Block 54 is preferably formed from Lucite or another material which will not corrode under the action of phosphorous or phosphoric acid. Block 54 has a plurality of sockets 55 formed therein and adapted to receive and support elongated sticks of phosphorus 56. A plurality of apertures 57 are formed in the block throughout the same and extend entirely through the block.

A shaft 58 passes through a stuffing box 59 carried by the bottom of water chamber 19. Shaft 58 is provided with a knurled hand grip 60 at its lower end, has a threaded engagement with the wall of water chamber 19 through which it passes, and bears against the bottom of block 54 at the center of said block.

The absorption chamber unit is mounted in a suitable opening in the upper wall 61 of water chamber 19 and is secured in operative relation to said water chamber by bolts 62 passing through the flanges 48 and into water chamber wall 61.

The operation of the device is as follows: A small stream of water is fed to aspirator 13 at intake 14 and exhausts into standpipe 16. As the water flows through the aspirator it draws the gas to be analyzed from intake 15 through the aspirator 13 and thence through conduit 24. The water which enters the standpipe fills the same within a certain interval, preferably operating in cycles of about two minutes each, and thus furnishes the motive power for the analyzer and controls the temperature and pressure of the gas sample. Thus, as the water rises in the standpipe 16, it passes upwardly in conduits 21 and 23 until it reaches the level in conduit 21 at which conduit 25 branches from conduit 21, all without interference to the continuous supply of gas by the aspirator in the following path: Conduit 24 to conduit 23 to conduit 22 to burette 20 to conduit 21 and through to conduit 25 to atmosphere. Thereafter as the water continues to rise in the standpipe and in conduits 21 and 23, the conduits 24 and 25 are shut off and a sample of gas is trapped in the burette 20 when the water in conduit 21 reaches the level at which conduit 26 branches from conduit 21. During this time the gas is forced into the atmospheric bag 27 to be measured at atmospheric pressure. When the water reaches a level completely sealing the connection between the conduits 21 and 26, there remains within the burette or measuring chamber 20, a sample of gas of a quantity accurately measured at atmospheric pressure. Hence the basis for an accurate determination of oxygen absorption in terms of percentage of volume is provided.

As the water continues to rise in the standpipe, and also conduits 21, 23 and associated conduits, including measuring chamber 20, the measured sample of gas is forced outwardly through conduit 22 which extends upwardly from water chamber 19 to a level slightly below the upper end of standpipe portion 18 and thence bends downwardly in a run 63, which is connected with the restricted opening 51 in neck 47 of the measuring chamber. A removable connector 64 is threaded on neck 47 to accommodate disconnection and separation of conduit 63 from the absorbing chamber, and thereby facilitate application and removal of the absorption chamber.

As the gas enters the absorption chamber from conduit 63 it comes into intimate contact with the

phosphorous sticks 56, thereby causing complete absorption of the oxygen component of the measured gas sample. The entry of the gas into absorption chamber 34 forces down the level of the water in said chamber, thus exposing the phosphorus and assuring the intimate contact of gas with phosphorus as aforesaid. This action forces some of the water out of absorption chamber 34 into the chamber 19 and up into the compression chamber 35. The normal level of the water in compression chamber 35 is in the plane of the bottom edge of the inner leg of siphon 37. The water is forced upwardly in compression chamber 35 until it reaches the level of the lower end of calibrating tube 36 thereby sealing said tube. Hence any further rise of the water level in chamber 35 forces the air which is trapped in the upper end of said chamber through the fitting 46 and conduit 45 to the operating mechanism of the recorder or indicator with which the device is supplied.

The positioning of the portion 18 of the standpipe to extend above the upper end of conduit assembly 22-63, provides a certain time lag between the time at which the gas is fully exhausted into the absorption chamber, and the time when the standpipe is completely filled. During this interval of time lag, the continued rise of water within the standpipe creates a pressure within the bell 42 which is transmitted through fitting 44 and conduit 43 to a second bellows of the indicator or recorder for cooperative action with the bellows which is connected with conduit 45 as aforesaid. When the water in the standpipe reaches a level slightly above portion 18 thereof, and at upper portion 30 of siphon 28, the standpipe is automatically emptied by the siphon. This allows the unabsorbed part of the gas sample in the compression chamber 34 to be pushed back into the measuring chamber 20, in preparation for repetition of the cycle above described. A fresh stream of gas is supplied by conduit 24 and passes through the measuring chamber 20 for exhaust at conduit 25 for about one-half minute before the water in the standpipe again reaches a level to close off the lower end of conduit 25. In this manner all gas residue from the preceding operation is swept out of the analyzer before a new sample is trapped. Also the water is permitted to rise in the absorption chamber 34 to the top thereof, to completely immerse the phosphorous sticks 56; thus washing the phosphorous pentoxide (P_2O_5) from the sticks.

As the water in the standpipe is discharged through siphon 28, it empties into the lower casing 12. This creates a pressure in the bell 41 which is transmitted through conduit 40 and forces some of the water out of supply tank 39 through tube 38 into compression chamber 35, thus assuring the maintenance of the desired water level in the water chamber 19 and compression chamber 35. When the water in casing 12 reaches the upper end of said casing, it starts its own siphon 31 and is discharged at 33 to a suitable drain. The emptying of casing 12 releases the pressure on bell 41, and causes any excess of water above the bottom end of tube 37 in compression chamber 35 to be syphoned back into tank 39. The above operation constitutes self leveling of the analyzer to bring the water in chamber 35 to the level of the lower end of tube 37 after each analysis, therefore eliminating all necessity for manual attention, and assuring positive accuracy.

The chamber 5 is preferably formed of such

capacity that it may wash all of the phosphorous pentoxide, formed in the full duration of operation of the device with one charge of phosphorous sticks, without creating too strong a solution of phosphoric acid within the chamber. In this way danger of corrosion of the tank and associated parts is substantially avoided. The use of Lucite in the block 54 has also been made to avoid corrosion. Suitable means are provided in the chamber 19 for draining the same as required, preferably at the same time the analyzer is recharged with phosphorous.

The primary advantage of the invention resides in the character of the absorption chamber 34. In this connection note that the shaft 58 provides means for adjusting the vertical position of the block 54 carrying the phosphorous sticks. This assures proper positioning of the phosphorous sticks at the upper end of the absorption chamber at all times, so that the full absorptive value thereof may be obtained. In practice, it is found that the deterioration of the phosphorous sticks incident to the formation of phosphorous pentoxide during an analyzer operation, is such that an adjustment of shaft 58 is generally required about once a day when used with a continuously operated recording type of analyzer as herein described. The conical formation of the interior tapered opening 50 in the head 46 of the absorption chamber is so designed and proportioned that, as the sticks of phosphorous 56 are pressed thereagainst by operation of shaft 58 aforesaid, said sticks will maintain their operative position and afford maximum exposed surfaces for the absorption operation.

When the sticks have been used to maximum permissible measure, determined by maximum possible adjustment of block 54 upwardly in casing 36, the absorption chamber may be removed as a unit by disconnecting fitting 64 from conduit 63, and by removing the screws 62. The absorption chamber can then be lifted bodily out of the water chamber 19, during which time the water is permitted to drain from housing 34 through passages 57 in block 54, thereby eliminating possibility of contact by the operator with any of the phosphoric acid formed in said water chamber 19 as aforesaid. It will also be seen that as chamber 34 is lifted out of chamber 19, block 54 will slide downwardly in chamber 34 to rest on the pins 53, which positively hold said block 54 and the residue of the phosphorous sticks 56 carried thereby within the chamber 34. Hence the operator does not have to handle the phosphorous sticks 56 at any time, and said sticks are in fact so guarded and shielded that it is impossible for the operator to touch the same.

The problem of disposal of the residue of the gas absorbing agent, such as phosphorous, is one which only such concerns or suppliers as have special equipment are in condition to solve; and hence it is desirable to provide some means by which the residue of the absorbing agent may be shipped by the user to the supplier of the phosphorous. For this purpose, I have provided the shipping container best illustrated in Fig. 3. This container comprises an outer casing 65 which is open at its upper end and is preferably exteriorly screw threaded to receive and mount a sealing cover or cap 66. An inner container 67 is positioned within the container 65, and has an outwardly extending flange 68 formed at its upper end and substantially below the upper end of chamber 65. The flange 68 is of an outer diameter to fit snugly in casing 65 and serves to

position the inner chamber 67 in spaced relation to the outer chamber 65 and against lateral movement. The absorbing chamber 34 is adapted to be positioned within the inner chamber 67, with its flange 48 bearing upon flange 68 of inner chamber 67, and preferably bolted thereto at 69. A cap 70 is threaded on the reduced neck 47 of head 46 of the absorption chamber to seal the upper end of said chamber. Inner chamber 67 is preferably filled with water in which the phosphorous sticks are immersed in transit. It will thus be seen that a safe and simple sealed container is provided by means of which the absorption chamber 34, with either a new or an exhausted charge of phosphorous sticks, may be shipped. The water within chamber 67 protects the phosphorous sticks from atmosphere while within the shipping container, thus preventing corrosion of the phosphorous and rendering the container safe to handlers. The cap 70, serving as it does to seal the upper end of reduced passage 51 in neck 47, prevents entry of air through said passage in the event the water level is not high enough to completely immerse the phosphorous sticks, as in shipping a new charge.

The only requirement for special care on the part of the operator of an instrument provided with my improved phosphorous cartridge as aforesaid, exists in connection with the operation of draining the water chamber 19 periodically to exhaust therefrom the phosphoric acid which forms therein. The cartridge itself is of such character that only by willful tampering on the part of the operator can he expose himself to contact with the phosphorous sticks. A further important advantage of the construction is that the apertured construction of the block 54 permits the free passage or flow of water through the absorption chamber or cartridge unit in the operation of the analyzer for the purpose of washing the phosphorous pentoxide from the phosphorous sticks after each absorbing operation, thereby assuring pure phosphorous surfaces for exposure to the gas sample throughout the entire operation of the analyzer.

I claim:

1. An absorption burette for a gas analyzer having a water container and means for measuring a gas sample and thence shifting said sample, comprising an absorption chamber adapted to be carried by and immersed in said container, means for supporting an absorbing agent in said chamber, said chamber having openings for entry of water therein to immerse said agent, other attachment means carried by said chamber for detachably connecting said chamber to said measuring means, other attachment means carried by said chamber for detachably securing said chamber to said container, said attachment means accommodating removal of said absorption chamber and its contents from

the analyzer as a unit in which said agent is fully confined, and means for adjustably positioning said agent supporting means in said chamber.

2. A removable absorption unit for a gas analyzer comprising a chamber, and a carrier in said chamber for supporting elements of gas absorbing material of predetermined shape in predetermined spaced relation to each other, said carrier having a plurality of restricted passages therethrough and being adjustable in said chamber, said chamber having an interior contoured portion against which the free portions of said elements press to maintain the same in operative relation.

3. An absorption unit for a gas analyzer comprising a chamber open at one end and having a restricted opening at its opposite end, a member slidable in said chamber having a plurality of sockets each adapted to receive one end of an elongated stick of phosphorus, said member having a plurality of restricted passages therethrough spaced from each other and from said sockets, and means for retaining said member in said chamber.

4. The construction defined in claim 3, wherein in the inner contour of said chamber at the end thereof having said restricted opening is tapered and adapted for abutment of the free end of said sticks thereagainst.

5. The combination with a casing open at one end and containing a gas absorbing agent, of a container having a water containing compartment receiving the open ended portion of said casing, said casing having a marginal projecting flange overlying the margin of said compartment to seal the same.

6. The combination with a casing for a gas absorbing agent which is open at one end and has a marginal projecting flange at its opposite end, of a container having a reduced dimension water compartment at its lower end defined by an inwardly projecting shoulder on which said flange seats with the open end of the casing in said compartment.

7. In combination, a casing for a gas absorbing agent having a neck at one end and open at its opposite end, said neck having a bore therethrough opening into the interior of said casing, a marginal flange projecting from said casing at the base of said neck, a container having a reduced dimension water chamber at its lower end defined by a shoulder on which said flange seats with the open end of the casing in said compartment, and a cover sealing said container.

8. The combination defined in claim 7, and means for detachably securing said flange to said shoulder.

9. The combination defined in claim 7, and means for sealing said neck bore.

CHARLES A. SPRAGUE.
